LAMBERT SCHMIDT, JR., OF BROOKLYN, NEW YORK, ASSIGNOR TO HIMSELF AND
LOUIS FREUND, OF NEW YORK, N. Y.

FUSE PLUG

Application filed March 23, 1928. Serial No. 264,263.

The invention relates to plugs for electrical circuits and especially to fuse plugs, and its object is to so construct or arrange such plugs as to prevent tampering with the circuit in which the plug is located.

For this purpose the plug is so constructed and arranged that it cannot be removed from its socket by ordinary means or manipulation. Or, as more particularly stated, the plug has at its outer end a manipulable member constructed and arranged to rotate the plug when turned in the direction to screw the plug into the socket, this member being also so constructed and arranged that when it is rotated in the opposite direction, in an effort to remove the plug, it rotates freely in relation to the plug, which therefore remains in the socket, protecting the socket terminals from being shorted by insertion of a metal object or instrument. The manipulable member, when the plug is in the socket, is the only practicably accessible part of the plug, and since its rotation is ineffective to remove the plug, unskilled or unauthorized persons find it practically impossible to remove the plug from the socket. Means is also provided by which authorized persons can remove the plug, such means preferably including a frangible member and a formation of the plug adapted for engagement by a simple implement to rotate the same for removal from the socket after the frangible member is broken.

A further object is to practically or entirely prevent the use of a fuse plug to provide an improper connection between socket terminals by cutting and bending one of the plug contact members. For this purpose the usual threaded shell or screw constituting one of the plug contacts, is replaced by a relatively narrow strip or segmental contact piece, which cannot practicably be manipulated or arranged to bridge the socket contacts.

The characteristics and advantages of the invention are further sufficiently explained in connection with the following detail description of the accompanying drawings, which show certain representative embodiments.

After considering these examples, skilled per-

sons will understand that many variations may be made, and I contemplate the employment of any structures that are properly within the scope of the appended claims.

Fig. 1 is a plan view of a fuse plug embodying the invention in one form, in position in a socket. 55

Fig. 2 is a section at 2—2, Fig. 1.

Fig. 3 is a side elevation of the plug, with a part broken away. 60

Fig. 4 is a top plan of a plug of modified construction.

Fig. 5 is a side elevation of the same, with a part broken away.

In Figs. 1 and 2, 1 is any ordinary plug 65 socket having a threaded contact shell 2 and a central bottom contact 3, these contacts being connected, respectively, to terminals or binding posts 4 and 5, which are in turn connected to conductors 6 and 7 of the fused 70 circuit.

The plug body 8, of insulating material, has a central or fuse-recess 9, an end or bottom contact 10 to engage socket contact 3, and a side contact 11 to engage socket contact 2. Contacts 10 and 11 are connected by the fuse strip 12 located in recess 9. As so far described the plug is of ordinary construction. Fuse plugs of this character are easily inserted in the socket, and as easily 80 removed, by rotary or screw action, and unauthorized or unskilled persons may therefore remove the plug at any time, giving access to the socket terminals. It is a quite common practice, when fuse 12 is "blown" 85 by an overload, and when a fresh fuse is not available, to remove the "blown" plug and bridge the socket terminals with a strip or piece of any available metal, which may sometimes be held in place by reinsertion of the "blown" plug. Thus, for example, a coin may be placed in the socket and held in position to bridge the socket terminals by inserting the plug 8. Such make-shift or substitute connections in a main circuit are, of 90 course, not calculated for proper maximum current flow, and upon occurrence of any overload will usually cause the blowing out of a number of "local" fuses or injury to electrical apparatus in the circuit, injury to the 95

100

circuit conductors or their insulation, short circuits or fires. Such make-shift fusing or connections in the circuit are therefore very undesirable and dangerous, and I therefore provide means, associated with the plug, to practically prevent its removal by unauthorized persons and thus prevent access to the socket terminals and improper connection thereof in the manner above mentioned.

The plug body has at its upper or outer end a thick flange 15. A manipulable member 16, usually of sheet metal, is secured to the outer end of the plug by cooperation with flange 15. The manipulable member or ring 16 includes an outer or end flange 17 overlying the outer end of the plug, a cylindrical or sleeve portion 18 overlying the periphery of flange 15, and an inturned flange or lip 19 underlying the inward face of flange 15. The member 16 is applied while the lip or flange 19 is in the form of a straight cylindrical extension of the sleeve portion 18, and the lip is then pressed or "spun" inward to engage under the plug flange 15 and retain the ring permanently in position so that it cannot be removed without destroying it. The ring has a slightly loose engagement with the plug; that is, it is revoluble upon the plug, except as such rotation in one direction is prevented by means to be described.

The outer margin of the outer end 20 of the plug is provided with any suitable plurality of ratchet notches 21, Fig. 3, each notch including a bevelled portion and an axially directed shoulder 22, these notches being all similarly arranged in a circular direction. The outer flange 17 of the manipulable member or ring 16, is cut and pressed to provide one or more (usually two) indent members or pawls 23. The sheet metal or ring 16 is resilient and the pawls 23 therefore resiliently engage the outer face 20 of the plug.

To insert the plug in the socket the periphery of ring 16 is grasped in the fingers, the end of the plug is applied to the socket, and the ring is rotated clock-wise, as viewed in Fig. 1. In this rotative movement the fingers or pawls 23 enter the ratchet notches 21 and their ends engage the shoulders 22, causing the plug to rotate along with the finger piece or ring for firm insertion in the socket in the usual manner. If it is attempted, for any reason, to remove the plug by reverse rotation in the usual manner, the finger piece or ring 16 will rotate freely in a counter-clockwise direction, as viewed in Fig. 1, the pawls or fingers 23 in this movement riding back over the inclines of the ratchet notches in the fashion of an ordinary ratchet device; or, in other words, the finger piece is operatively disconnected from the plug and has no capacity to rotate it. Unauthorized persons, therefore, upon attempting to remove the plug, find it is impracticable to

do so by any ordinarily available means, or without destroying the plug.

The outer end of the fuse recess 9 is ordinarily closed by a mica disc 25 located in a shallow face-recess 26 in the outer end of the plug and retained by a metal fitting or ring similar to the ring 16, but not provided with any means such as here disclosed to operatively connect the ring with the plug in one direction of rotation, and to operatively disconnect it in the other direction. My present ring and ratchet construction is adapted for the proper location and retention of such a mica closure disc 25 by arranging the ratchet notches 21 and pawls 23 in outward marginal portions of the plug face and ring flange 17, respectively, so that the pawls are located outside the periphery of the mica disc, and the inner margin 27 of flange 17 overlies the outer margin of the disc and retains it permanently in position, secure against removal, except by breaking the disc or destructive injury to ring 16. The recess 9 is thus sealed and the inner members of the plug terminals are inaccessible for connection by a make-shift fuse or short-circuiting device.

To enable the plug to be easily removed by authorized persons, means are provided by which the plug may be rotated in reverse or left-hand direction by application of a suitable tool or simple implement, usually after rupturing some part of the plug structure—preferably the mica cover disc 25. Thus, in the present structures, the fuse recess 9, near its outer end, is provided with irregularities or has a polygonal socket formation, such as the square formation shown at 30, Figs. 1 and 4. After breaking the mica seal 25, any convenient implement, such as the squared or flat end of a wooden stick may be inserted into the polygonal formation 30 and the plug reversely rotated by this implement, after which a fresh plug may be inserted in the usual way.

The outer contact member of these plugs is usually in the form of a threaded shell of continuous or sleeve form, to engage the threaded socket shell 2. After a fuse is "blown" this plug contact or shell is sometimes cut and bent downward in such position as to bridge the socket terminals when the plug is reinserted, this, of course, producing an improper fusing or shorting of the circuit. To prevent such unauthorized or dangerous manipulation of the plug, whether or not it is provided with means such as above described for preventing its removal from the socket, I preferably substitute for the outer or shell contact, a notch or strip contact 40, Figs. 2 and 3, embedded in or overlying the side of the plug in a longitudinal direction. This strip is usually threaded, as at 41, to correspond with the thread formation of the socket shell 2, and since the strip or segment

40 is so narrow that this threading will usually be insufficient for the proper screw-connection, threads 42 are preferably formed in the plug body so that the threads 41 of 5 the strip 40 form segments of the complete annular screw threads. The lower end 43 of the contact piece may be embedded in the material of the socket in process of manufacture, and the upper portion 44 passes through 10 the socket wall for connection to one end of the fuse strip, as usual. The contact strip or piece 40 is so small that it is not practicably available for bridging the socket terminals by cutting and bending it in such a manner as 15 above described.

Figs. 4 and 5 show a modification of the ratchet connection between the manipulable ring 16 and the plug body. In this arrangement the plug flange 15 has a peripheral 20 channel 50, in the inner face of which ratchet notches 51 are formed. Ring 16 is provided with a ratchet device consisting of a piece 25 of spring wire 52, bent to circular form and having one end connected to the sleeve portion 18 of the ring, as by soldering at 53, and to facilitate the soldering operation an aperture may be formed in the ring sleeve at that point. The other end of the spring wire is bent to form a tooth or pawl 54 30 to cooperate with the ratchet notches 51 in substantially the same manner and for the same purpose as described with reference to Figs. 1 to 3.

Evidently other ratchet structures or arrangements may be provided, and other features of construction may be varied without departing from the principles disclosed.

A plug can be manufactured according to this invention at the same, or less expense, 40 than the ordinary plug not having the safety features disclosed herein.

I claim:

1. A plug adapted for insertion in an electric socket and having contacts to cooperate 45 with the socket contacts, comprising a body, a manipulable member thereon accessible for grasping and insertion of the plug, and means by which rotation of the manipulable member in one direction is effective to rotate the plug and produce engagement between the plug and socket contacts, and rotation of the manipulable member in the other direction is ineffective to rotate the plug or disconnect the plug and socket contacts.

2. A plug adapted for insertion in an electric socket and having contacts to cooperate with the socket contacts, comprising a body, a manipulable member revolubly mounted 50 on an outward portion of the plug, and means acting in one direction of rotation of said member to rotate the plug therewith, said means when said member is rotated in the reverse direction being ineffective to rotate 55 the plug.

3. A plug adapted for insertion in an electric socket and having contacts to cooperate with the socket contacts, comprising a body, a manipulable member revolubly mounted on an outward portion of the plug, 70 and ratchet mechanism intermediate the plug body and said member to produce rotation of the body when the member is rotated in one direction while permitting the member to be rotated in the opposite direction without rotative effect upon the plug body.

4. A safety fuse plug comprising a body having a fuse recess and contacts to cooperate with socket contacts, a fuse in the recess connecting the plug contacts, a manipulable 80 member loosely mounted on an outward portion of the plug, and means by which rotation of said member in one direction produces corresponding rotation of the plug body and rotation of the member in the other 85 direction is ineffective to rotate the plug body.

5. A safety fuse plug comprising a body having a fuse recess and contacts to cooperate with socket contacts, a fuse in the recess 90 connecting the plug contacts, a manipulable member loosely mounted on an outward portion of the plug, and means by which rotation of said member in one direction produces corresponding rotation of the plug 95 body and rotation of the member in the other direction is ineffective to rotate the plug body, the plug body having a formation to cooperate with an implement for rotating the body in a direction to remove it from the socket.

6. A plug adapted for insertion in an electric socket and having contacts to cooperate with the socket contacts, comprising a body, a manipulable member thereon accessible for 100 grasping and insertion of the plug, and means by which rotation of the manipulable member in one direction is effective to rotate the plug and produce engagement between the plug and socket contacts, and rotation of the 105 manipulable member in the other direction is ineffective to rotate the plug or disconnect the plug and socket contacts, the body having near its outer end a polygonal implement-receiving formation adapted to cooperate with 110 an inserted implement by which the body may be rotated and removed from the electric socket.

7. A safety fuse plug comprising a body having a fuse recess and contacts to cooperate 120 with socket contacts, a fuse in the recess connecting the plug contacts, a manipulable member loosely mounted on an outward portion of the plug, and means by which rotation of said member in one direction produces corresponding rotation of the plug body and rotation of the member in the other direction is ineffective to rotate the plug body, the fuse recess having near its outer end a polygonal 125 socket formation adapted for cooperation 130

with an inserted implement to rotate and remove the plug from the electric socket.

8. A safety fuse plug comprising a body having a fuse recess and contacts to cooperate with socket contacts, a fuse in the recess connecting the plug contacts, a frangible seal for the outer end of the recess, a manipulable member loosely mounted on an outward portion of the plug and means by which rotation of said member in one direction produces corresponding rotation of the plug body and rotation of the member in the other direction is ineffective to rotate the plug body.

9. A safety fuse plug comprising a body having a fuse recess and contacts to cooperate with socket contacts, a fuse in the recess connecting the plug contacts, a frangible seal for the outer end of the recess, a manipulable member loosely mounted on an outward portion of the plug and means by which rotation of said member in one direction produces corresponding rotation of the plug body and rotation of the member in the other direction is ineffective to rotate the plug body, the fuse recess near its outer end having a formation to cooperate with an implement inserted after rupture of the frangible seal, whereby the body may be rotated in a direction to remove it from the socket.

10. A safety fuse plug comprising a recessed body having contacts to cooperate with socket contacts, a body having a flange at its outward end, an annular manipulable member revolvably mounted on the body in cooperation with the flange, and ratchet mechanism intermediate said member and the body, effective to rotate the body with said member when the latter is rotated in one direction, and ineffective to rotate the body when the member is rotated in the opposite direction.

11. A safety fuse plug comprising a recessed body having contacts to cooperate with socket contacts, a body having a flange at its outward end, and a sheet metal manipulable member having portions embracing the body flange and overlying the outer face of the body, said member having revoluble engagement with the body, and ratchet means intermediate said member and the body.

12. A safety fuse plug comprising a recessed body having contacts to cooperate with socket contacts, a body having a flange at its outward end, an annular manipulable member revolvably mounted on the body in cooperation with the flange, an outer part of the body having ratchet notches, and one or more ratchet members carried by said member and adapted to cooperate with the notches.

13. A safety fuse plug comprising a recessed body having contacts to cooperate with socket contacts, a body having a flange at its outward end, and a sheet metal manipu-

lable member having portions embracing the body flange and overlying the outer face of the body, the outer face of the body being provided with ratchet notches, and the overlying portion of said manipulable member having ratchet members to cooperate with the notches.

14. A safety fuse plug comprising a recessed body having contacts to cooperate with socket contacts, a body having a flange at its outward end, and a sheet metal manipulable member having portions embracing the body flange and overlying the outer face of the body, the outer face of the body being provided with ratchet notches, and the overlying portion of said manipulable member having portions cut and indented to form pawls to cooperate with the notches.

In testimony whereof I affix my signature.
